UNITED STATES PATENT OFFICE.

HYMAN ELI GOLDBERG, OF CHICAGO, ILLINOIS.

PHOTOPRINTING APPARATUS.

1,113,550.

Specification of Letters Patent.

Patented Oct. 13, 1914.

Application filed January 22, 1912. Serial No. 672,560.

To all whom it may concern:

Be it known that I, HYMAN ELI GOLDBERG, a citizen of the United States, residing at Chicago, in the county of Cook and State 5 of Illinois, have invented a certain new and useful Improvement in Photoprinting Apparatus, of which the following is a specification.

It is well known by those familiar with 10 the art of printing in general that photographic printing, for instance photolithography, has many advantages over other processes—stereotyping for example—but that for several reasons it has never been 15 used in general newspaper work at least for printing ordinary letter press matter, stereotyping being the method usually employed for the larger dailies. There have heretofore been no means known by which photographic printing could be used in general 20 newspaper work, especially for the printing of written articles.

In order that the quality and scope of 25 my invention may be more readily understood it may be of advantage to briefly indicate the present state of the art of photolithography and some of the reasons why it could not heretofore be applied to newspaper work: In ordinary photolithographic 30 work the drawing, design or printed matter is drawn or printed upon translucent material of some kind, usually thin paper. This piece of paper, which will be referred to as the "copy" is in ordinary commercial 35 photolithography pasted upon a "stick-up" sheet also of some translucent material. A number of these copy slips or sheets are usually pasted upon the stick-up sheet in order to economize time in handling the 40 sensitized plate. The stick-up sheet is then pressed closely against the face of the sensitized plate and light is caused to pass through the stick-up sheet and copy to act upon the sensitized surface of the plate. 45 This method serves well enough in commercial photolithography where the time factor is not of vital importance but it is quite impractical for the composing room of modern metropolitan dailies where the time 50 factor is of the utmost importance. The handling of the thin copy sheet and the time required to adjust and paste them on the stick-up sheet would be prohibitive, especially as it is the custom with the larger 55 newspapers to divide an article or "story" of any considerable length into a number

of sections and these are handed to a number of linotype or monotype operators who work on the sections simultaneously and thereby get the articles set up in a very short 60 time. It is evident that there would not be time to prepare stick-up sheets of the size of a newspaper page when the copy sheets are so small and numerous. Furthermore, there would be an added difficulty in newspaper work for the following reasons: In photolithography as ordinarily practised the copy sheets are cut to a size considerably 65 larger than the area occupied by the actual printed design to afford marginal space for receiving the paste to hold the copy sheet to the stick up sheet. The paste is usually applied in dabs near the corners of the copy sheet, these dabs not being applied within the area occupied by the printed matter for 70 they would interfere with the passage of light and produce imperfect results. In newspaper work, however, the columns come so closely together that there is no room for these marginal pasting areas on the copy 75 sheets.

Another consideration is this: In the larger metropolitan dailies which print several editions, it is customary in the later editions to cut down the space allotted to 80 the stories appearing in the earlier editions. This is usually done by omitting parts of the story, for instance, by omitting or "pulling" paragraphs. With ordinary photolithographic processes where the copy sheets 85 are pasted upon the stick up sheets it would be impossible or at least impractical to thus "pull" portions of the story, for it would require unpasting of certain portions. My apparatus lends itself particularly to these 90 conditions, for any number of type units may be abstracted from the "set up"; that is the filled tray or galley or chase and the spaces filled by merely sliding the type units 95 up close together to fill the gap.

With the above consideration in mind, the general object of my invention is to provide means whereby the photoprinting process may be practically applied to newspaper work and similar printing, where the conservation of time and location of the copy sheets are of controlling importance.

More especially, the object of my invention is to provide a type (by which I mean to include a single letter or a line of letters 110 or a plurality of lines of letters or a drawing or design as far as the same may be consid-

ered a single unit) having an opaque face and a transparent or translucent body, the whole constituting a "type unit" and this type unit having substantial thickness whereby it may serve as a gage or "locator" for the adjacent type units.

Another object of the invention is to provide apparatus adapted to hold a "set up" of these type units in contact with the face 10 of the sensitized plate, the apparatus being also provided with means for passing light rays through the set up to the sensitized plate.

Other objects of the invention relate to 15 details of construction which will be hereinafter more specifically described.

I obtain my object by the type and apparatus illustrated in the accompanying drawings, in which—

20 Figure 1 is a perspective view of a characteristic single letter "type unit." Fig. 2 is a perspective view of a type unit bearing a design or drawing. Fig. 3 is a type unit bearing a complete line. Fig. 4 is a vertical 25 sectional view of a type frame forming a part of my invention, the type being shown in position therein. Fig. 5 is a perspective view of the tray which forms part of the frame or holder. Fig. 6 is a sectional detail 30 of a tray having fixed marginal lines. Fig. 7 is a sectional detail similar to Fig. 6, but showing a tray in which the marginal lines or partitions are removable. Fig. 8 is a perspective view of a marginal line adapted for 35 use in the form of tray shown in Fig. 7. Fig. 9 is a sectional detail showing another form of modification in the form of tray. Fig. 10 is a fragmentary view showing a portion of a tray having stops of a modified 40 form. Fig. 11 is a perspective view of a multiple line type unit having transverse scoring or rows of perforations to facilitate the breaking up of the unit for the purpose of removing or inserting lines. Fig. 12 is a 45 fragmentary top view of a multiple line unit having notches at the edges for gaging the unit for a cutter for the purpose of separating the unit into different parts between the lines for the purpose just mentioned in 50 connection with Fig. 11. Fig. 13 is a sectional view showing the thickness of a multiple line type unit showing transverse grooves to facilitate the separating of the unit between the lines as described in connection with Figs. 11 and 12.

Similar numerals refer to similar parts throughout the several views.

Referring first to the form of type unit shown in Fig. 1, the type body 1 consists 60 of a block of transparent or translucent material, for example, glass, celluloid, et cetera. On top of this is a copy sheet 2 having printed, drawn or otherwise portrayed thereon the type face 3. This type face is 65 opaque and consists, for example, of print-

ers' ink, drawing ink, bronze or the like. The copy sheet consists usually of thin paper or other substance which will form a background for the type face and at the same time permit light to pass through it. The 70 type body is of substantial thickness, the actual dimension depending upon the circumstances and the conditions of material and use, but in any event the thickness is great enough to enable the type unit to hold its shape, to permit it to be handled without damage, and to enable it to maintain its position laterally and also act as a gage or locator for adjacent type units. In other words, the type unit as a whole is thick and 75 strong enough to prevent lateral movements of itself and adjacent type units by mere contact of its edges with surrounding type units or other objects.

The type unit shown in Fig. 2 is similar 80 in all respects to that shown in Fig. 1, the only difference being that the type face is in the form of a drawing or design. Fig. 3 is also similar except that the type face consists of a whole line of type. The type 85 units shown in Figs. 11, 12 and 13 are multiple line units adapted to be separated between the lines for the insertion or removal of one or more lines. The multiple line 90 units will be hereinafter again referred to. 95

The precise method of manufacture of the type units is immaterial. Under ordinary circumstances the type faces will be printed upon the copy sheets 2 and the latter will be secured by paste, fusion or otherwise to the 100 type body. The type body is then cut to size or, if preferred, the type body may be previously cut to size and the copy sheet secured thereto in proper position. The type 105 units when completed are rectangular in outline and for ordinary newspaper printing have a width equal to that of a column or multiples thereof.

I will now describe suitable apparatus for 110 utilizing my type units in the photoprinting process: Referring first more particularly to Figs. 4 and 5, the rectangular stationary frame 10 is supported upon suitable legs 11. This frame is open at the center and supports at the edges a transparent 115 plate 12. Upon this rests a tray 13 which is also transparent. In the form shown in Fig. 5 this tray has a number of parallel guides or partitions 14 located at a distance apart equal to the width of the column of the newspaper or book to be printed. These 120 partitions may be a permanent part of the frame, as shown at 14^a, Fig. 6, or may be removably secured by dowel pins, as shown at 14^b, Figs. 7 and 8. Their sides may be 125 vertical, as shown in Figs. 5, 6, 7 and 8, or tapered as shown at 14^c, Fig. 9. In the latter case the type bodies 1^a will have correspondingly tapered sides. The partitions 130 may be non printing, as shown at 14^a and

14^b, Figs. 6 and 7, or printing, as shown at 14^d and 14^e, Figs. 6 and 7 respectively. In the latter case the top of the partition will rise flush with the surface of the type unit 5 so as to contact with the sensitized plate hereinafter mentioned and carries an opaque line on the top to thereby produce a line upon the plate which will print when the latter is finished. These partitions are of 10 a width equal to the width between the proximate edges of two adjacent printed columns of the newspaper and the opaque line on the top is of a width equal to the width of the line to be printed between the 15 columns on the final printed page, and the "printing" partitions are beveled at the top so that the line produced will be as narrow as the ordinary "column lines" or marginal lines of a newspaper.

20 In use, the type units rest face upward upon the tray, as shown in Figs. 4, 6, 7 and 9. Next above the tray and type units is placed the sensitized plate 30 with the sensitive surface downward. Above this is a 25 backing 15, upon which rests a cover 16. Said cover is preferably composed of wood and closely fits within the frame. Exhaust pipes 17; 18, 19 lead from the frame 10 to a header 20 which is connected to the receiver of an air pump (not shown) or other 30 means for exhausting the air from between tray 13 and the plate 30 and thereby producing the desired close contact between the type faces and the sensitized surface of the 35 plate. Lamps 21, preferably of the Cooper-Hewitt variety, now commonly used in photolithography, are mounted in the frame beneath the transparent bottom plate 12. Beneath these lamps is a mirror 22 for reflecting and diffusing the rays from the lamps.

40 In operation, after the type units are finished (and in newspaper work they are usually of the width of a column) they are placed face upward in the tray 13, where 45 they hold themselves in position by means of each other and the partitions of the tray. The sensitized plate and cover 16 are then adjusted, whereupon the air is exhausted to produce close contact, after which the light 50 is turned on and the operator proceeds as in the ordinary photolithographing process.

I have already suggested that by the term "type unit" I do not confine myself to a single line of type for a number of lines 55 may occur upon the same type body; in fact, my invention contemplates using one or more paragraphs upon a single type body, the essential idea being not the number of lines but the idea of forming the 60 copy upon self holding blocks of transparent or translucent material which may be readily handled, the blocks having sufficient substance to hold their shape.

It is within the purview of this invention 65 that the type body when formed of a height

more than a single line be formed between the lines, as shown at 26, Fig. 11, so that the unit may be broken up into a plurality of units by mere tearing or breaking. This renders it possible to remove or replace any 70 number of lines without destroying the lines which it is desired to retain. Instead of perforating, the multiple line units may be notched, as shown at 27, Fig. 12. These notches being located between the lines serve 75 to locate the knife or cutter. Other methods of facilitating parting of the multiple line units may be employed, for example transverse grooves 28, shown in Fig. 13. These may be used either for weakening 80 the type unit to thereby control the line of fracture, or it may serve to receive a gage upon an ordinary cutting machine.

It is not essential that the type body consist of glass, celluloid or the compounds 85 analogous to celluloid for under certain conditions a light-transmitting variety of bristol board may be used, especially if treated with oil or some substance to enhance its light transmitting quality. 90

I have described the vertical partitions or stops for columnar printing. Other forms of stops may be employed, for example, the pegs or knobs 25 shown in Fig. 10. These may be either removable or integral with the tray, and are especially adapted for book printing for they serve to locate the type units which produce the different pages. 95

Having thus described my invention, 100 what I claim as new and desire to secure by Letters Patent is:—

1. In combination, type units having a transparent body and an opaque face, the type body being of substantial thickness, 105 and a transparent tray having transparent stops thereon for holding the type units in position.

2. In combination, type units having a transparent body and an opaque face, the type body being rectangular in outline and of substantial thickness, and a transparent tray having a partition adapted to hold the type units in position laterally. 110

3. In combination, type units having a transparent body and an opaque face, the type body being of substantial thickness whereby one type unit may hold itself and other type units by mere edge-contact, a transparent tray for said type unit and 115 transparent partitions in said tray for holding said type units in columns. 120

4. In a photoprinting outfit the combination of type units having a transparent body and an opaque type face, the type body being rectangular in outline and of substantial thickness, a rectangular transparent tray for holding said type units and a removable partition for dividing said type units into parallel columns. 125 130

5. In a phototyping outfit the combination of type units having a transparent body and an opaque type face, the type body being rectangular in outline and of substantial thickness, a rectangular transparent tray for holding said type units and a transparent stop on said tray for holding the type units in position upon the tray, said stops having opaque portions coming flush with 10 said type face for protecting the sensitized plate from the action of light.

6. In a phototyping outfit the combination of type units having a transparent body and an opaque type face, the body being 15 rectangular in outline and of substantial

thickness, a transparent tray for holding said type unit and a partition for holding said type units in columns, said partition having thereon an opaque line which comes flush with the type faces whereby both the 20 type faces and the partition protect the sensitized plate from light action.

In witness whereof, I have hereunto subscribed my name in the presence of two witnesses.

HYMAN ELI GOLDBERG.
